FISHERMAN'S HAT

Sam W. Brunner, New York, N. Y.

Application January 27, 1945, Serial No. 574,885

9 Claims.

(Cl. 2—185)

This invention relates to an improvement in hats, particularly hats for fishermen, and comprises an improved device which may constitute an integral part of a hat or merely an attachment adapted to be applied to the hat at will.

More specifically my invention is directed to a device of the character indicated, to be used by fishermen, for carrying leaders and artificial flies, the invention having for one of its objects to provide a device for these purposes which, as noted above, may constitute an integral part of the hat or be employed merely as an attachment.

A further object of the invention is to provide a device of the class indicated whereby not only may fly hooks be temporarily secured thereto very quickly and readily removed, but the user has the assurance that the hook will not become dislodged accidentally.

A still further object of my invention is to provide a device of the character indicated which is adapted for the reception and temporary storage of leaders, thereby eliminating the necessity for the conventional leader box, my construction being such that the leaders are kept moist and hence ready for immediate use.

Other objects will appear hereinafter.

In the accompanying drawing:

Fig. 1 is a perspective view showing an embodiment of my invention;

Fig. 2 is a section taken on the line 2—2 of Fig. 1; and

Fig. 3 is a view similar to Fig. 2 of another embodiment of the invention.

Referring to the drawing in detail, and first of all to Figs. 1 and 2: In this embodiment my invention has been incorporated into a hat so as to constitute an integral part of the same.

2 designates the brim and 4 the crown of a hat to which my invention is applied. The brim 2 of my improved hat is composed of a plurality of outer flexible plies 6 and 8 and intermediate plies 10 and 12.

The outer faces of upper and lower plies 6 and 8 are either treated as by coating or impregnating to render the same moisture and water resistant, as indicated at 14 and 16, or I may employ a layer of waterproof material for this purpose, just as desired.

The material of the plies 6 and 8 is preferably water absorbent, although other flexible material may be employed if desired. The intermediate layers 10 and 12 are of felt or some other highly water absorbent material, and one or both of these layers or plies preferably is remov-

able. In the drawing, ply 10 has been shown fixed in position while 12 is removable.

The purpose of the construction so far described is to provide for the temporary storage of leaders in the hat brim. It is quite obvious that in use it is merely necessary to spread the plies of the brim and coil the leaders about the crown 4. I have shown leaders in this position at 18.

10. It will be appreciated that it is a simple matter to remove the ply 12 which is in the form of an annulus, wet the same and then replace it in position.

The leaders are not only kept in a moistened condition, but are protected against the sun, so that they are ready for use at all times. The necessity of the conventional leader box is eliminated, and because my device provides for laying the leaders up in a large coil as compared with the relatively narrow coil which is necessary when storing in a leader box, the leaders are in much better condition than when the leader box is used.

It will be appreciated also that when changing 25 casts, it becomes unnecessary to remove the fly from the leader. It is much simpler merely to detach the leader of one cast from the line and store the leader and fly in the hat brim and attach another leader and fly to the line. Then if it becomes desirable to use the old cast it is ready for immediate use.

In addition to the foregoing I provide the hat crown 4 with a construction for the temporary attachment of artificial flies 20.

30. This construction embodies a continuous strip 22 of material such as felt, for example, extending about the hat crown 4. This strip is provided with a central longitudinal groove 24 through which the felt is stitched to the crown, as shown at 26. By stitching at the groove 24 the flies 20 can be hooked into the felt without catching the hook in the stitches 26, which is of advantage in that it not only facilitates attachment of a fly to this strip but eliminates loosening or breaking of the stitches 26, thereby to prolong the useful life of the hat as a whole.

If desired the brim of the hat may be provided adjacent its periphery with snap fasteners 28.

It will be seen from all of the foregoing that in the embodiment of my invention so far described my invention has been incorporated into the hat structure itself.

As above noted, my invention may constitute an attachment for hats, that is, a device which can be slipped on and off an ordinary hat as desired.

Referring to the construction illustrated in Fig. 3: A hat brim has been shown at 2 and a hat crown at 4.

My attachment which is simply slipped over the hat crown 4 into superimposed position relative to brim 2 comprises a band member 28 adapted to encircle the crown 4 and brim plies 30 and 32 overlying the hat brim 2. The outer surfaces of these plies are shown covered with a sheet 34 of waterproof material, any number of which are available. A rubberized fabric is one example. On the other hand, it is within the purview of my invention merely to impregnate these surfaces of the plies 30 and 32 with a waterproofing material. The material 34 when used is stitched to the band member 28 as shown at 36.

The plies 30 and 32 are of felt or other water absorbent material. Intermediate these plies I provide one or more annuli 38 of felt or other water absorbent material. This intermediate layer is unattached to the plies 30 and 32 so as to be removed whenever desired to dampen the same. The leaders 18 are simply stored between 30 and 38 and between 32 and 38 as shown.

The band member 28 may carry a strip such as the felt 22 of Fig. 2 for retaining fly hooks, or I may perforate and slit the same as shown at 40 so that the point of a hook may be slipped between 28 and the hat crown 4 as illustrated in the drawing.

It will be seen from all of the foregoing that I have provided a construction which is well adapted for the purposes for which it has been designed.

It is to be understood that the embodiments illustrated and described are in the nature of illustrative examples, and that changes in construction and arrangement of parts can be made without departing from the spirit and scope of my invention.

What I claim is:

1. A leader-storage brim for fishermen's hats, said brim comprising a flat annulus adapted to be slipped over the hat crown so as to lie flat in superimposed parallel relation to the hat brim, said annulus comprising a plurality of superimposed water and moisture absorbent annuli attached to each other along their inner edges, the material of the annuli being flexible to permit the annuli to be spread apart at their peripheries to enable leaders to be inserted therebetween and wound about the hat crown.

2. A leader-storage brim for fishermen's hats, said brim comprising a flat annulus adapted to encircle the hat crown and to lie flat in superimposed parallel relation to the hat brim, said annulus comprising a plurality of superimposed flexible annular plies united to each other along their inner edges but separable throughout the remainder of the brim to provide for the winding or coiling of one or more leaders between the plies about the area of union of the plies to each other.

3. A leader-storage brim for fishermen's hats, said brim comprising a plurality of superimposed flexible annular plies united to each other along their inner edges but separable throughout the remainder of the brim, the outer surfaces of the brim thus provided being water and moisture repellent, the inner surfaces being water and moisture absorbent.

4. A fisherman's hat comprising in combination

5 a crown and a brim, the brim comprising a plurality of superimposed annuli of flexible material, said annuli being separable at the brim periphery so that they may be spread apart to permit leaders to be inserted between the annuli for winding about the hat crown.

5. An attachment for fishermen's hats for the storage of leaders, said attachment comprising an annulus adapted to encircle the hat crown and to lie flat in superimposed relation to the brim thereof, said attachment being composed of a plurality of superimposed plies united to each other along the inner periphery of the annulus but separable throughout the remainder of the attachment whereby a leader may be coiled between the plies about the union of the plies to each other.

6. An attachment for fishermen's hats, said attachment comprising an annulus adapted to encircle a hat crown in superimposed relation to the hat brim, said attachment being composed of a plurality of superimposed water and moisture absorbent layers or plies, the exterior surfaces of the brim being water and moisture resistant, the several layers or plies being united to each other about the inner periphery of the annulus but separable throughout the remainder of the annulus, to provide for the reception of one or more leaders between the water and moisture absorbent portions of the plies or layers and coiling of the same about the area of join or union of the plies or layers to each other.

7. An attachment for fishermen's hats, said attachment comprising a multi-ply leader-receiving brim and a hook-retaining band integral with one of the plies of the brim, the brim and band being 35 so relatively disposed as to be slipped over a hat crown into position where the band encircles the crown and the multi-ply brim overlies the hat brim, the inner surfaces of the plies of the brim being of water and moisture absorbent material.

8. An attachment for fishermen's hats, said attachment comprising a brim of multi-ply material and a hook supporting band attached thereto, the brim and band being so relatively disposed as to be slipped over a hat crown into position where the band encircles the crown and the brim overlies the hat brim, the brim being composed of water and moisture retaining material and the plies thereof being separable throughout except at the area of attachment to the band to permit one or more leaders to be coiled about the crown of the hat and retained between the plies of the brim in contact with the water and moisture retaining surfaces thereof.

9. An attachment for fishermen's hats for the temporary storage of leaders, said attachment comprising an annulus adapted to encircle the hat crown and to lie flat in superimposed relation to the hat brim, said attachment being composed of a plurality of superimposed layers one of which extends inwardly and upwardly to provide a crown-encircling hat band, said layers being united to each other adjacent the inner periphery of the annulus, but separable throughout the remainder of the attachment whereby a leader may be coiled for storage between the plies constituting said annulus about the union of the plies to each other.

SAM W. BRUNNER.
